ATTORNEY

UNITED STATES PATENT OFFICE.

EDITH FRITZ, OF BROOKLYN, NEW YORK.

PAPER-FILE.

1,354,819.

Specification of Letters Patent.

Patented Oct. 5, 1920.

Application filed December 17, 1917. Serial No. 207,603.

To all whom it may concern:

Be it known that I, EDITH FRITZ, a citizen of the United States, residing at Brooklyn, in the county of Kings and State of New York, have invented certain new and useful Improvements in Paper-Files, of which the following is a specification.

This invention relates to paper filing devices for clippings and the like.

10 The object of the invention is to provide a simple and efficient device of this character so constructed that in order to remove a paper strung thereon all that is necessary is to slip the various papers around until the 15 required paper is reached and then open the file and remove the paper.

Another object is to provide an annular file formed of a strip having its ends detachably connected so that the papers strung 20 thereon may be shifted similar to keys on a key ring and the ring then opened, the paper removed, and the ring again closed.

Another object is to so connect the ends 25 of the split ring that the papers may be slid around over the joint without being retarded or torn.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made without 30 departing from the spirit of the invention,

35 in the scope of what is claimed without departing from the spirit of the invention,

In the accompanying drawings:—

Figure 1 represents a side elevation of a 40 file constructed in accordance with this invention,

Fig. 2 is a detail side elevation partly in section showing the joint connecting the ends, and

Fig. 3 is a transverse section taken on the 45 line 3—3 of Fig. 2.

The annular file constituting this invention is preferably constructed of a piece of heavy wire of any desired length according to the size of the ring which it is desired to 50 form. One end of the wire strip 1 is enlarged as shown at 2 and provided with a longitudinally extending socket 3 into which

the end 4 is designed to fit. This socket 3 corresponds approximately in diameter to the diameter of the end 4 which end carries 55 a nib or enlargement 6 at its terminal and said socket has an annular groove or recess 5 formed in one side wall to receive the nib or enlargement 6 on the end 4, said nib springing into the groove 5 when end 4 reaches the limit of its inward movement 60 and thereby retains the ends connected.

In the use of this improved file, papers of any character, such as receipts and the like, 65 may be strung thereon by separating the ends 2 and 4 and using the smaller end 4 to puncture the papers. After the desired number have been placed thereon these ends are interlockingly engaged by inserting one 70 within the other.

When it is desired to remove a paper, all that is necessary is to locate the paper desired to be removed, then slide the others around on the ring until the desired paper is positioned adjacent the joint which connects 75 the ends 2 and 4. The ring is then opened by pulling out the end 4 from the socket 3, the paper taken off, and the ring again closed.

It will be seen that by so connecting the 80 ends of this ring the papers may be moved around in the direction of the arrow *a* without encountering any obstructions, hence any retarding of the movement of the papers is avoided and all possibility of their becoming 85 torn is prevented.

From the foregoing description, taken in connection with the accompanying drawings, the advantages of the construction and of the method of operation will be readily 90 apparent to those skilled in the art to which the invention appertains and while I have described the principle of operation of the invention together with the device which I now consider to be the best embodiment 95 thereof, I desire to have it understood that the device shown is merely illustrative and that such changes may be made as are within the scope of the claimed invention.

I claim:—

100 A paper file composed of a strip of heavy wire having one end enlarged and provided with a longitudinally extending socket of a size to receive the other end, said socket

having an annular groove in one side wall at its inner end, the end for insertion in the socket having a nib at its terminal, said nib springing into said groove when the end 5 carrying it reaches the limit of its inward movement, whereby said ends are held connected.

In testimony whereof I affix my signature in presence of two witnesses.

EDITH FRITZ.
